CLAIM

The ornamental design for a chime unit for a video doorbell, as shown and described.

DESCRIPTION

FIG. 1 is a top, front side perspective view of a chime unit for a video doorbell showing our new design;

FIG. 2 is top plan view thereof;

FIG. 3 is a bottom plan view thereof;

FIG. 4 is front elevation view thereof;

FIG. 5 is a rear elevation view thereof;

FIG. 6 is a left side elevation view thereof; and,

FIG. 7 is a right side elevation view thereof.
